(57) **CLAIM**

The ornamental design for a sequencing instrument, as shown and described.

DESCRIPTION

FIG. 1 is a right side perspective view of an embodiment of a sequencing instrument in accordance with the present invention.

FIG. 2 is a left side perspective view of the sequencing instrument of FIG. 1.

FIG. 3 is a front view of the sequencing instrument of FIG. 1,

FIG. 4 is a rear view of the sequencing instrument of FIG. 1.

FIG. 5 is a left side view of the sequencing instrument of FIG. 1.

FIG. 6 is a right side view of the sequencing instrument of FIG. 1.

FIG. 7 is a top view of the sequencing instrument of FIG. 1; and,

FIG. 8 is a bottom view of the sequencing instrument of FIG. 1. The broken lines immediately adjacent the shaded areas represent the bounds of the claim, and all other broken lines are directed to the environment. The broken lines form no part of the claimed design.

1 Claim, 8 Drawing Sheets
